UNITED STATES PATENT OFFICE.

JOHN W. McMILLAN, OF MARSHFIELD, MASSACHUSETTS.

DESIGN FOR A CASING FOR WEIGHING-MACHINES.

47,539.

Specification for Design.

Patented July 6, 1915.

Application filed April 16, 1915. Serial No. 21,921. Term of patent 14 years.

To all whom it may concern:

Be it known that I, JOHN W. McMILLAN, a citizen of the United States, residing at Marshfield, in the county of Plymouth and State of Massachusetts, have invented a new, original, and ornamental Design for a Casing for Weighing-Machines, of which the following is a specification, reference being had to the accompanying drawing, forming part thereof.

In the drawing I show a perspective of a casing embodying my design as seen from the front.

What I claim is:

The ornamental design for a casing for a weighing machine, as shown.

JOHN W. McMILLAN.
